UNITED STATES PATENT OFFICE.

WILHELM BIEGER, OF HEILBRONN-ON-THE-NECKAR, GERMANY, ASSIGNOR
OF ONE-HALF TO WILHELM RUDOLPH, OF GIessen, GERMANY.

PIANO-PLATE.

SPECIFICATION forming part of Letters Patent No. 739,380, dated September 22, 1903.

Application filed February 3, 1903. Serial No. 141,682. (No model.)

To all whom it may concern:

Be it known that I, WILHELM BIEGER, a subject of the King of Würtemberg, residing at Heilbronn-on-the-Neckar, in the Kingdom 5 of Würtemberg, German Empire, have invented certain new and useful Improvements in Piano-Plates, of which the following is a specification.

My invention relates to improvements in piano-plates.

In fitting piano-plates of prior constructions the sounding-board bridge is secured directly to the sounding-board and the iron bars for connecting the hitch-pin plate to the wrest- 15 pin plate are so arranged that they only oppose the pull of the strings on one side, so that a strong wooden or iron structure behind the sounding-board is necessary.

The present invention relates to a piano- 20 plate of such construction that a one-sided pull of the strings is avoided, the pull being transferred to the main portion of the plate—*i. e.*, to the dead-point—so that there is no leverage. This is effected by iron bars being 25 provided between the sounding-board and the sounding-board bridge for the purpose of directly connecting the hitch-pin plate with the wrest-pin plate below the level of the strings.

The accompanying drawings illustrate one 30 form of the invention.

Figure 1 is a plan of the plate located on the sounding-board with stretched strings. Fig. 2 is a plan of the plate without the stringing. Fig. 3 is a section taken on the line A A 35 of Fig. 2. Fig. 4 is a section on the line B B of Fig. 1.

As Fig. 1 shows, the sounding-board bridge *a* is not secured directly to the sounding-board *b*, but rests on the stiffening-ribs *c* of 40 the board *b*. These ribs in prior constructions are not located, as here, on the top of the board, but on the under side or back. It is not, however, absolutely essential according to the present invention to arrange these

wooden ribs *c* on the top of the board, as the 45 figure shows. They may also be located, as formerly, below—that is, on the under side of the sounding-board—and between the bridge *a* and the latter blocks, wooden rosettes, or the like are provided, so that the sounding- 50 board bridge is elevated a suitable distance from the board in order to furnish sufficient space for a series of lower bars *d*. The arrangement of these bars *d*, Fig. 2, forms the essential feature of the present invention. 55 As is seen from the drawings, they connect the hitch-plate pin *e* directly to the wrest-pin plate *f* below the strings and are so located that the sounding-board bridge *a* lies between the lower bars *d* and the ordinary upper 60 bars *g*.

What I claim as my invention, and desire to secure by Letters Patent, is—

1. The combination in a piano, of a plate, a sounding-board, a sounding-board bridge and 65 upper bars with lower bars the latter arranged between the sounding-board and the sounding-board bridge and directly connected to the hitch-pin plate and to the wrest-pin plate below the level of the strings, substantially as 70 set forth.

2. In a piano, the combination of a plate, a sounding-board, a sounding-board bridge, upper bars and lower bars the latter arranged 75 between the sounding-board and the sounding-board bridge and directly connecting the hitch-pin plate to the wrest-pin plate below the level of the strings, with strengthening-ribs provided on the top of the sounding-board to serve as support for the sounding-board bridge, substantially as described.

In testimony whereof I have signed my name to this specification in the presence of two subscribing witnesses.

WILHELM BIEGER.
